UNITED STATES PATENT OFFICE.

WALTER M. AUSTIN, OF SWISSVALE, PENNSYLVANIA.

FOUR-CYCLE INTERNAL-COMBUSTION ENGINE.

1,115,477.

Specification of Letters Patent.

Patented Nov. 3, 1914.

Application filed October 23, 1912. Serial No. 727,335.

To all whom it may concern:

Be it known that I, WALTER M. AUSTIN, a citizen of the United States, residing at Swissvale, in the county of Allegheny and State of Pennsylvania, have invented new and useful Improvements in Four-Cycle Internal-Combustion Engines, of which the following is a specification.

This invention relates to internal combustion engines, and more particularly to that type in which the combustible mixture is compressed prior to ignition.

In what is known as the four cycle engine there are four strokes. The first stroke 15 draws in the charge of combustible mixture, the second stroke compresses the charge, in the third stroke the charge is ignited, and on the fourth stroke the engine cylinder is scavenged or cleared of the products of combustion. It is highly desirable in order to 20 secure the maximum efficiency and reliability, that the engine cylinder be cleared of the products of combustion as completely as possible on the scavenging stroke, so that when a fresh charge of combustible mixture 25 is taken into the engine cylinder, the same will not be contaminated with burnt or inert gases which tends to vitiate the mixture and render the ignition point more uncertain.

The ignition stroke should also be as long 30 as possible in order to utilize the expansive force of the ignited mixture to the largest extent. On the compression stroke a certain amount of clearance space must be provided 35 for the compressed charge of combustible mixture, while the suction stroke does not need to be as long as the ignition stroke, in order to draw in that amount of combustible mixture which would be the most economical. It will thus be evident that to secure 40 the best efficiency, the four strokes of the engine should be of variable length, the scavenging stroke being such as to practically drive out all the products of combustion, the ignition stroke being longer than 45 the suction stroke, and the compression stroke being such that a clearance space remains at the end of the stroke.

The principal object of my invention is 50 to provide an internal combustion engine of the four cycle type having improved means for securing variable strokes of the above described character.

Another object of my invention is to increase 55 the range of regulation of an internal combustion engine.

Other objects and advantages of my invention will appear in the following more detailed description of my invention.

In the accompanying drawings, Figure 1 60 is a central vertical section of an internal combustion engine embodying my improvements; Fig. 2 a horizontal section thereof on the line B—B of Fig. 1; Fig. 3 a detail view of the connecting rod of the engine; 65 Fig. 4 a section of the connecting rod on the line A—A of Fig. 3; Fig. 5 a central vertical section of the engine piston at right angles to the section shown in Fig. 1; Fig. 6 a detail view of the collar employed as an 70 abutment for each valve spring; Fig. 7 a detail view showing the application of said collar to a valve stem; Fig. 8 a section of the main crank shaft portion of the engine on the line C—C of Fig. 1; Fig. 9 a dia- 75 grammatic view showing the relative positions of the parts at the end of the expansion stroke; Fig. 10 a similar view of the parts at the end of the exhaust stroke; Fig. 11 a similar view at the end of the suction stroke; 80 Fig. 12 a similar view at the end of the compression stroke; and Fig. 13 a diagram showing the path described by the center of the rotating end of the connecting rod for a complete cycle. 85

I preferably accomplish the objects of my invention by connecting the end of the engine connecting rod with an eccentric or auxiliary crank device, which auxiliary crank is in turn rotatably mounted on the 90 crank pin of the main crank shaft. According to my invention means are provided for causing the auxiliary crank shaft to rotate about the main crank pin one half of a revolution for each whole revolution of 95 the main crank shaft. Preferably this is accomplished by providing an internal gear secured to the auxiliary crank and meshing with a stationary gear having its axis common with the axis of the main crank shaft. 100

As shown in Fig. 1 of the drawings, the cylinder casing 1 of the internal combustion engine is provided with the usual water cooling space 2 having an inlet port 6 and outlet port 7. Within the cylinder 1 is a 105 piston chamber 38 containing the piston 33 and having the usual opening 5 for the insertion of a spark plug. The cylinder casing 1 may extend to the center line of the main crank shaft 13 and the crank case 8 110 is secured to the cylinder casing by means of bolts (not shown). The hub 9 of a sta-

tionary spur gear 10 is clamped in position when the crank casing is fastened to the cylinder casing and forms a bearing for one end of the main crank shaft 13. Said 5 crank shaft is preferably supported on ball bearings, the ball bearing 11 at one end being secured in position by the crank and cylinder casings, and the other ball bearing 12 being secured within the stationary gear 10. The connecting rod 22 is operatively attached to the piston 33 through cross head 31 and oscillates on a ball bearing 30. The opposite end of the connecting rod 22 is operatively connected to the crank pin 14 of 10 the main crank shaft through an eccentric or auxiliary crank 17, preferably provided with a ball bearing. On one side of the eccentric 17 is an inlet valve operating cam 15 and on the opposite side thereof is an 15 exhaust valve operating cam 16, each cam preferably having a ball bearing support on the main crank shaft.

Preferably formed integrally with the cam 16 is an internal gear 19 meshing with 20 the stationary gear 10 and the cams 15 and 16 are secured to the eccentric 17 by means of bolts 18.

The engine inlet and exhaust valves 34 and 35 are preferably mounted on the head 25 of the piston 33 and are provided respectively with valve stems 39 and 45. On each valve stem is mounted a spring 41 tending to hold the valve closed, a slotted collar 40 being provided to act as an abutment for 30 the spring. The valve stem is also slotted on opposite sides so as to leave a thickness equal to the width of the slot and the collar is provided with an annular recess 46 of 35 the same diameter as the valve stem so that the collar may be slipped onto the valve stem at the slotted portion and then allowed 40 to drop in position with the round portion of the valve stem fitting within the recess of the collar, as shown in Fig. 7. For operating the inlet and exhaust valves, a valve 45 rod 26 is mounted on each side of the connecting rod 22 in position to engage the projecting ends of the valve stems 39 and 45.

The piston end of the connecting rod is 50 provided with a guide member 29 having bearings within which the rods 26 reciprocate. The crank end of the connecting rod is also provided with a guide member 28 slotted to form guide bearings for the opposite ends of the valve rods 26. Said opposite end of each valve rod is provided with jaws 55 25 between which is mounted a roller 23 on a pin 24. The rollers 23 are adapted to engage the contact faces of the cams 15 and 60 16 and are maintained in contact therewith by means of springs 27 held under compression between the guide members 29 and the jaws 25. The cam 15 is provided with a projecting portion 20 adapted to engage the 65 end of the valve rod for the inlet valve 34

at the proper time to open same and the cam 16 is provided with a projecting portion 21 adapted to engage the end of the valve rod for the exhaust valve 35 to open same at the desired time. 71

An inlet port 3 is provided in the cylinder casing 1 which supplies the combustible mixture to a chamber 36 in the piston 33 and as said chamber is open to the valve 34, when said valve lifts, the combustible mixture is admitted to the piston chamber 38. An exhaust outlet 4 is also provided which communicates with an exhaust chamber 37 contained in the piston 33 and upon opening the exhaust valve 35, the piston chamber 38 75 so is vented to the atmosphere. 80

In order to secure two revolutions of the main crank shaft for one of the auxiliary cranks, the pitch diameter of the internal gear 19 is made equal to twice the diameter 85 of the main crank circle and the pitch diameter of the stationary gear 10 is made equal to the diameter of the main crank circle. The internal gear 19 has a planetary movement about the stationary gear 10 and 90 for every revolution of the main crank shaft the internal gear and its connected parts rotate one half of a revolution with respect to the axis of the internal gear. 95

In operation, assume the parts in the position shown in the diagram, Fig. 11, a charge of combustible mixture having been drawn into the piston chamber. If the parts rotate in the direction indicated by the arrows, the main crank moves upwardly from 100 the position shown in Fig. 11 to the position shown in Fig. 12. The internal gear 19 moves around the stationary gear 10 and with it the auxiliary crank 17 and while the main crank is making approximately the 105 half revolution from the position shown in Fig. 11 to the position shown in Fig. 12, the auxiliary crank makes one-fourth of a revolution about its axis in the same direction. The charge of combustible mixture is now 110 compressed into the clearance space shown in Fig. 12, and the charge being ignited in the usual manner, the piston moves downwardly to the position shown in Fig. 9, the main crank having made substantially a 115 complete revolution while the auxiliary crank has only made one-half of a revolution. In this further movement of the main crank one-half a revolution, the auxiliary crank moves about its axis another one-fourth revolution and the parts assume the 120 position shown in Fig. 10, this stroke being the exhaust stroke and the piston being shifted nearly to the cylinder head as shown. On the next stroke, the piston moves downwardly and a charge of combustible mixture is drawn in, thus completing the cycle. The projecting portion 21 engages the valve rod of the exhaust valve every fourth or exhaust 125 stroke of the piston, as the auxiliary crank 130

5 makes only one revolution for two revolutions of the main crank shaft, while the inlet valve 34 is opened by the engagement of the projecting portion 20 of cam 15 on the suction stroke and on the other two strokes of the engine both valves are held closed.

10 In Fig. 13 is shown the path described by the lower end of the connecting rod, the same being in the form of a double loop marked D D and the circle C being the path 15 of the crank pin 14 as it revolves about its center O. The lines connecting the circle C with the curve D D indicate different positions of the auxiliary crank. The distance S indicates the relative length suction stroke, the distance T the compression stroke, the distance U the expansion stroke, and the distance V the exhaust stroke.

15 It will be noted that the exhaust port 4 is so located that it is opened directly to the space above the piston near the end of the expansion stroke, so that any gas in the cylinder above atmospheric pressure is permitted to escape before the opening of the 20 exhaust valve, while on the shorter suction stroke the exhaust port is covered by the piston 33.

25 When both the inlet and exhaust valves are placed in the engine piston, it is evident 30 that the outside diameter of each valve is limited to one-half the diameter of the piston and if larger valves are necessary, as might be the case in a very high speed engine, one valve only, preferably the inlet 35 valve, may be placed in the piston while the exhaust valve is put in the cylinder head.

40 Other forms of gear connections may be employed, within the scope of my invention, but I consider the arrangement shown in the drawings as the preferable one and one which will operate with a minimum amount 45 of friction. It will also be obvious that other forms of auxiliary cranks may be employed and that it is not necessary to use the specific construction illustrated in the drawings.

Having now described my invention, what I claim as new and desire to secure by Letters Patent, is:—

50 1. In an internal combustion engine, the combination with a cylinder, a piston therein, and a main crank, of an auxiliary crank operatively connecting said main crank to said piston, a stationary gear, and an internal gear meshing with said stationary gear and having its pitch diameter twice the pitch diameter of the stationary gear, said gears being operatively connected to said auxiliary crank for causing movement there- 55 of about its axis.

55 2. In an internal combustion engine, the combination with a cylinder, a piston therein, and a main crank, of an auxiliary crank operatively connecting said main crank to said piston, a stationary gear having a pitch

diameter equal to the diameter of the circle described by the main crank, and an internal gear meshing with said stationary gear and having a pitch diameter twice the pitch diameter of the stationary gear, said internal gear being secured to the auxiliary crank for causing one revolution of said auxiliary crank about its axis for two revolutions of the main crank.

3. In an internal combustion engine, the combination with a cylinder, a piston therein, and a main crank, of an auxiliary crank mounted on the main crank, a valve controlling a port opening into the cylinder, and means for operatively connecting said auxiliary crank to said piston and valve.

4. In an internal combustion engine, the combination with a cylinder, a piston therein, and a main crank, of an auxiliary crank mounted on the main crank for operating said piston, a valve controlling a port opening into the cylinder, and means operating through the movement of said auxiliary crank for controlling said valve.

5. In an internal combustion engine, the combination with a cylinder, a piston therein, a connecting rod for said piston, and a main crank having a crank pin, of an auxiliary crank mounted in said piston for controlling a port opening into said cylinder, and an auxiliary crank mounted on said crank pin for operating said valve and also the piston connecting rod.

6. In an internal combustion engine, the combination with a cylinder, a piston therein, a connecting rod for said piston, and a main crank having a crank pin, of an inlet valve and an exhaust valve mounted in said piston for controlling an inlet port and an exhaust port to and from said cylinder and an auxiliary crank mounted on said crank pin for operating said valves and also the piston connecting rod.

7. In an internal combustion engine, the combination with a cylinder, a piston therein, and a main crank having a crank pin, of a valve mounted in said piston for controlling a port opening into said cylinder, an auxiliary crank mounted on the main crank shaft for operating said piston, means for effecting a rotary movement of said auxiliary crank about its axis, and a cam member operatively connected to said auxiliary crank for operating said valve.

8. In an internal combustion engine, the combination with a cylinder, a piston therein, and a main crank having a crank pin, of a valve mounted in said piston for controlling a port opening into said cylinder, an auxiliary crank mounted on the main crank shaft for operating said piston, means for effecting a rotary movement of said auxiliary crank about its axis at the rate of one revolution while the main crank shaft makes two revolutions, and a cam member

carried by said auxiliary crank for operating said valve.

9. In an internal combustion engine, the combination with a cylinder, a piston there-in, and a main crank shaft, of a valve in said piston for controlling a port opening into said cylinder, a valve stem for said valve, a connecting rod operatively connecting said main crank shaft to said piston, a 10 valve rod carried by said connecting rod for operating said valve through said valve stem, and an auxiliary crank mounted on said crank shaft for operating said valve rod.
15. 10. In an internal combustion engine, the combination with a cylinder, a piston there-in, and a main crank shaft, of an auxiliary

crank mounted on said main crank, a connecting rod for operatively connecting said auxiliary crank to said piston, means for rotating said auxiliary crank about its axis one-half a revolution for one revolution of the main crank, a valve mounted in said piston, a valve rod carried by said connecting rod for operating said valve, and means 20 mounted on said auxiliary crank for operating said valve rod.

In testimony whereof I have hereunto set my hand.

WALTER M. AUSTIN.
